(57) **CLAIM**

The ornamental design for a teleprompter, as shown and described.

DESCRIPTION

FIG. 1 is an upper perspective view of a teleprompter; FIG. 2 is a bottom perspective view of the teleprompter of FIG. 1;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a perspective view of the teleprompter of FIG. 1 in a using status; and,

FIG. 10 is a perspective view of the teleprompter of FIG. 1 in another using status.

Broken lines are for illustrating portions of the teleprompter which form no part of the claimed design.

1 Claim, 10 Drawing Sheets
